UNITED STATES PATENT OFFICE.

JOHN R. GAMMETER, OF AKRON, OHIO, ASSIGNOR TO THE B. F. GOODRICH COMPANY,
OF NEW YORK, N. Y., A CORPORATION OF NEW YORK.

FLUID-PRESS FOR RUBBER FOOTWEAR.

1,232,787.

Specification of Letters Patent. Patented July 10, 1917.

Application filed December 29, 1915. Serial No. 69,268.

To all whom it may concern:

Be it known that I, JOHN R. GAMMETER, a citizen of the United States, residing at Akron, in the county of Summit and State 5 of Ohio, have invented certain new and useful Improvements in Fluid-Presses for Rubber Footwear, of which the following is a specification.

This invention has for its object to provide improved means for compacting the parts of a lasted rubber shoe preparatory to vulcanization, and thus dispense with a considerable part of the hand rolling which has formerly been required.

15 My invention involves the action of compressed air or other suitable pressure fluid directly upon the outer surface of the sole and the adjacent portions of the upper, and also the use of a flexible diaphragm of appropriate shape, which may be distended by fluid pressure, for sealing the mouth or opening of the shoe, the interior of the shoe being preferably vented to the atmosphere. Novel provision is made for controlling the 20 diaphragm and the supply and discharge of compressed air, and for quickly removing and replacing the diaphragm when required.

Of the accompanying drawings,

30 Figure 1 represents a vertical sectional view of a fluid shoe press embodying my invention.

Fig. 2 represents a top plan view showing the interior of the pot with a shoe in place, and the fluid-pressure connections.

35 Fig. 3 represents a transverse section of the shoe pot.

Fig. 4 represents an elevation of the controlling valve device as viewed from the 40 left in Fig. 2.

Figs. 5, 6, and 7 represent horizontal sectional views showing the controlling valves in different positions.

Fig. 8 represents a plan view of the shoe 45 pot with its cover down.

Fig. 9 represents an enlarged vertical section of a portion of the last and its support.

Fig. 10 represents a plan view of the last supporting plate.

50 Fig. 11 represents a vertical section showing the last-holding plunger.

Referring to the drawings, 20 represents a rubber-shoe pressing pot open at the top and having a cover 21, whose edge and the

upper rim of the pot are provided with 55 complementary interlocking projections 22, 23 separated by recesses, to afford a quick locking and unlocking action by rotation of the cover, the latter being pivoted at 24 on an arm 25 which is hinged at 26 to the 60 side of the pot, said cover having a handle 27 for rotating it, and the edge of the cover being packed by a gasket 28. The cover is provided with a glazed window 29 (Fig. 8) through which the shoe and diaphragm 65 may be observed, and the interior is illuminated in any suitable way, as by means of an electric bulb 30 (Fig. 1) placed directly in the pot.

31 represents a last with a rubber shoe 32 70 thereon, placed in the pot 20 bottom-side up and supported by a plate 33, the latter having a suitable number of vertical pins and the last a corresponding number of holes for properly centering or positioning the 75 last, there being shown here a single pin 34 occupying a hole 35 in the last which preferably extends through to the sole in order to assist in venting the interior of the shoe, although the escape of the air from between the shoe and the last takes place principally through the shoe opening. The squeezed-out air escapes to the outer atmosphere through grooves and holes 36, 37 (Figs. 9 and 10) in the plate 33. The said 80 35 plate has a hollow stem 38 and its under side has an annular rib 39 forming an air-tight joint with the diaphragm 40, hereinafter described, and clamped against said diaphragm by a bolt 41 engaging a perforated 90 cap or bridge-piece 42.

Diaphragm 40 is a flexible sheet of soft rubber vulcanized in the form of a cup whose cavity approximates the shape of the foot or last in a zone about midway between 95 the sole and the ankle, and whose upper margin is formed with a flange secured by plate 43 and screws 44 (Fig. 2) to the upper edge of a cup-shaped plate or receptacle 45, forming with the diaphragm a fluid-pressure chamber 46. This receptacle and the diaphragm I prefer to make as a single unit which may be readily removed upwardly from the pot 20 when it is desired to change a diaphragm which may have become defective or to substitute one of a different size. The receptacle 45 is held in place by a bolt 47 and yoke 48 (Fig. 3),

and its joint with the bottom wall of pot 20 is sealed by a ring of packing 49.

To hold the last down against plate 33, I provide a vertical pin or plunger 50 on the pot cover 21, said plunger having a heel-engaging head 51 at its lower end, a knob 52 at its upper end, a spring 53 mounted in a cylindrical casing 54 to raise the plunger, and circular ratchet teeth 55 on its stem, engaged by a pawl 56 which is projected by a spring 57 (Fig. 8), to hold the plunger down against the last after it has been manually depressed, the plunger being moved horizontally into and out of coöperative relation with the pawl by the locking and unlocking movement of the cover. The heel of the pawl engages a stop 58 on the cover arm 25 when cover 21 is turned clockwise (as viewed in Fig. 8) to unlock it from the rim of pot 20, and the plunger is thereby automatically released from the pawl.

Any suitable pressure fluid may be used in chamber 46 for distending and collapsing the diaphragm 40, but I prefer a liquid (such as water) because of its incompressibility. A vent pipe 59 leads from the upper part of chamber 46 to the atmosphere and is provided with a cock 60 for releasing air from said chamber.

The compacting of the sole and adjacent parts of the upper of the rubber shoe is performed by a suitable pressure fluid such as compressed air acting directly thereon in the pot 20, this air being admitted and discharged through a pipe 61 under control of a plug valve 62 in a casing 63, said valve alternating the connection of pipe 61 with a compressed-air pipe 64 and an exhaust port 65.

The escape of any substantial quantity of compressed air around the neck of the last or into the space between the shoe and the last is prevented by the diaphragm 40 acting as a contractile gasket or packing. For the purpose of actuating the diaphragm, I find it desirable to connect the interior of chamber 46 by a pipe 66 with the interior of a forcing chamber 67 having a movable wall or septum 68 at its leftward limit, as viewed in Fig. 1, and the pot 20 at atmospheric pressure. Cover 21 being thrown back on the hinge 26, a lasted shoe is inserted in the pot, the cover closed and turned by handle 27 to lock it, and the plunger 50 pushed down to hold the last in place. Handle 81 is then turned clockwise through 90° to the position shown in Fig. 6, which connects the water-supply pipe 78 with pipe 76, but does not move the air valve 62. Septum 68 is thereby forced to the right until the follower 72 meets the stop 74, and water is thus forced from chamber 67 through pipe 66 into chamber 46, distending the diaphragm 40 to its dotted-line position, shown

of sizes and shapes of lasts, and as the necessary amount of distention varies accordingly, it will be observed that the stop member 74 performs a highly important function. Obviously, although omitted from the drawing, a suitable pointer may be provided on the stem of the screw stop, coöperating with a stationary index for indicating the proper position for the different sizes of lasts.

The pressure fluid for chamber 69 may be water taken from a city main and supplied to said chamber through a pipe 76 under control of a plug valve 77 in the casing 63, which alternates the connection of pipe 76 between a water-supply pipe 78 and a discharge pipe 79. In the pipe 78 is a check valve 80 preventing the return of water therethrough.

The two valves 62, 77 are operated by a single handle 81 whose hub-plate 82 turns loosely on the stem of the air valve 62 and is connected to operate said air valve with lost motion by a pin 83 on its hub plate working against the ends of a slot 84 formed in a plate 85 which is attached to the stem of said valve. 86 is a plate fixed to the stem of the water valve 77. Said plate 86 and the hub plate 82 are provided with interacting mutilated gear segments 87, 88 and 95 stop faces 89, 90, 91, 92 in order that the initial movement of handle 81 from its position in Figs. 2 and 5 may open the water valve 77, and its final movement in the same direction may open the air valve 62 through the pin 83 and slot 84.

93 is a by-pass pipe connecting the diaphragm chambers 67, 69 and containing a cock 94, whereby the necessary volume of water may be provided in chamber 67, pipe 105 66, and chamber 46 to give the diaphragm 40 the desired amount of distention for a given setting for the stop-screw 74.

In the operation of my apparatus, the handle 81 should first be turned to the position shown in Figs. 2 and 5 so that the air and water valves 62, 77 are venting their respective chambers 46 and 69, which will leave the diaphragm 40 collapsed, septum 68 at its leftward limit, as viewed in Fig. 1, and the pot 20 at atmospheric pressure. Cover 21 being thrown back on the hinge 26, a lasted shoe is inserted in the pot, the cover closed and turned by handle 27 to lock it, and the plunger 50 pushed down to hold the last in place. Handle 81 is then turned clockwise through 90° to the position shown in Fig. 6, which connects the water-supply pipe 78 with pipe 76, but does not move the air valve 62. Septum 68 is thereby forced to the right until the follower 72 meets the stop 74, and water is thus forced from chamber 67 through pipe 66 into chamber 46, distending the diaphragm 40 to its dotted-line position, shown

in Fig. 1, so that it forms an effective packing around the mouth of the shoe. When the distention has ceased, as observed through the window 29, handle 81 is given 5 a further quarter-turn to the position shown in Fig. 7, and the air valve 62 thereby connects air-supply pipe 64 with pipe 61 without any further change in the position of the water valve, compressed air being thus 10 admitted to the interior of pot 20 so as to act on the sole and upper of the shoe 32 and cause the parts of the shoe to be thoroughly compacted, the reaction of the cushion formed by the water-backed diaphragm 40 15 serving to compact those portions of the upper with which said diaphragm is in contact as well as to seal the mouth of the shoe. After leaving the air pressure on for a few minutes, handle 81 is moved back to 20 its initial position and the air and water valves are thus successively moved to their discharge positions, whereby atmospheric pressure is restored in the pot 20 and chamber 69 is relieved so that the springs 73 may 25 retract the septum 68, thus sucking the excess water out of chamber 46 and collapsing the diaphragm 40, whereupon cover 21 may be opened and the pressed shoe removed.

30 This apparatus dispenses with practically all of the hand rolling heretofore required except for the back seam and the edges of the sole.

I claim:—

- 35 1. A rubber-shoe press comprising a pot having a support for the lasted shoe, a fluid-distensible diaphragm for packing the shoe opening, and adapted to leave the bottom portion of the shoe exposed, and means for 40 supplying pressure fluid to the interior of said pot, for direct contact with said exposed portion of the shoe.
2. A rubber-shoe press comprising a lasted-shoe container, means for admitting 45 pressure fluid thereinto to surround and press directly upon the shoe, and a liquid-backed member for packing the shoe opening against access of said pressure fluid to the inside of the shoe.
- 50 3. A rubber-shoe press comprising a pressure pot, a flexible packing member thereon having approximately the shape of a shoe last in a zone between the sole and ankle, and means for supplying pressure fluid to the interior of said pot.
- 55 4. A rubber-shoe press comprising a pot having means for supporting a lasted rubber shoe and exposing the same directly to the action of a fluid under pressure, a chamber 60 having a shoe-packing diaphragm as one wall, a body of liquid substantially filling said chamber, and means for varying the volume of said liquid body.
- 65 5. A rubber-shoe press comprising a pot having means for supporting a lasted rub-

ber shoe and exposing the same directly to a pressure fluid, a chamber having a flexible wall for packing the shoe opening, a body of liquid substantially filling said chamber, and means including a non-return valve for supplying and retaining said liquid.

6. A rubber-shoe press comprising a pot having a support for a lasted shoe, a diaphragm for packing the shoe opening, and means for supplying two different fluids under pressure to opposite sides of said diaphragm.

7. A rubber-shoe press comprising a pot having a support for a lasted shoe, a diaphragm for packing the shoe opening, means for supplying two different fluids under pressure to opposite sides of said diaphragm, and interconnected valves for controlling the respective fluids.

8. A rubber-shoe press comprising a pot having a support for a lasted shoe, means for supplying a compacting fluid under pressure to the interior of said pot, a compacting-fluid controlling-valve, a flexible diaphragm for packing the shoe opening, means for supplying a fluid under pressure to distend said diaphragm, a diaphragm-fluid controlling-valve, an operating handle, and connections therefrom to the respective valves adapted first to move the diaphragm-fluid valve to an admitting position while the compacting-fluid valve remains in its discharge position, and then to move the latter to an admitting position while the former remains in its admitting position, and, upon reversal of the handle, to move said valves so as first to discharge the compacting fluid and then the diaphragm fluid.

9. A shoe press comprising a shoe-pressing body of liquid, means including a septum, a septum-chamber, conduit structure and controlling-valve mechanism, for separately supplying and discharging liquid to project and retract said body of liquid, and a non-return valve in the supply conduit for said separate liquid.

10. A shoe press comprising a shoe-pressing diaphragm, a body of liquid for distending and collapsing the latter, diaphragm and septum chambers in open connection for containing said liquid body, a yieldingly-retracted septum for actuating the liquid body, and means for applying fluid pressure to project said septum.

11. A shoe press comprising a shoe-pressing diaphragm, a body of liquid for distending and collapsing the latter, a variable-stroke liquid actuator, and an adjustable stop for said actuator.

12. A shoe press comprising a shoe-pressing diaphragm, a body of liquid for projecting and collapsing the latter, a yieldingly-retracted variable-stroke septum for actuating said liquid body, an adjustable stop

for limiting the projecting movement of said septum, and means for applying fluid pressure to said septum to project the latter.

13. A shoe press comprising a shoe-pressing diaphragm, diaphragm and septum chambers in open connection for containing a body of water to distend and collapse said diaphragm, a septum forming a wall of said septum chamber, a water-pressure chamber on the opposite side of the septum, and a by-pass conduit connecting said septum chamber and water-pressure chamber and having a hand valve.

14. A rubber-shoe press comprising a pot having a support for the top of the last in a lasted shoe, sole engaging means for clamping the lasted shoe against said support, means for packing the shoe in a zone adjacent the ankle of the last, and means for supplying compressed air to the interior of said pot to compact the walls of the shoe.

15. A rubber-shoe press comprising a container pot, a distensible diaphragm for packing the shoe opening, a hold-down member for supporting the shoe against the thrust

of said diaphragm, and means for supplying pressure fluid to the interior of said pot.

16. A rubber-shoe press comprising a container pot having a movable cover, a support for the lasted shoe, a flexible member for packing the shoe opening, means for supplying pressure fluid to the interior of the pot, a spring-retracted plunger mounted on said cover for holding down the last, and means for automatically catching and retaining said plunger in its hold-down position.

17. A rubber-shoe press comprising a container pot having a cover hinged to open and close and rotatable to lock and unlock, means for supporting a lasted shoe in said pot, means for applying fluid pressure thereto, a hold-down member for the last mounted on the cover, a catch therefor, and means actuated by the unlocking movement of the cover for releasing said catch.

In testimony whereof I have hereunto set my hand this twenty-third day of December, 1915.

JOHN R. GAMMETER.
